5 Claims. (Cl. 179—16)

1

The present invention relates to pulse receiving and repeating circuits for telecommunication systems using signaling impulses of alternating current either at a frequency in the voice frequency range or at some other predetermined particular frequency which is convenient in light of available apparatus. The system herein described and claimed is related to that described and claimed in my copending application Serial No. 661,493, filed April 12, 1946, now Patent No. 2,462,144, issued February 22, 1949.

The signal receiving and/or repeating circuits to which this invention relates should be sensitive, conveniently adjustable, and faithful in reproduction. A variety of relays are customarily employed for this purpose, among those frequently used are the out-of-phase flux relays which may comprise either one or two magnetic circuits. In the former case, a phase difference of the flux in the useful air gap is artificially produced by a phase shifting device. Relays of either of the above types have the disadvantages of narrow adjustment limits, contact vibrations, and a limited number of faithful repetitions even when a pulse-correcting system is used during each retransmission.

Another known arrangement of a receiving member utilizes an assembly consisting of a dry rectifier, a polarized two-winding relay, and a condenser. While such a device is preferable to those named above, its chief drawbacks are bulky construction and high cost.

An object of the present invention is to avoid the shortcomings of the prior arrangements by providing simple and effective means for the internal switching of signaling circuits.

Another object of the present invention is to provide a pulse receiving and repeating system of great sensitivity and high operating dependability.

A further object of this invention is to provide a pulse receiving and repeating means having virtually no inertia, permitting reception and/or repetition of short pulse trains such as those emitted by an automatic dial.

A further object of the invention is to provide a system of the type contemplated which is operable by signal current either at a frequency in the voice frequency range or at some other particular frequency convenient in light of the available apparatus in a telecommunication system.

In a pulse receiving and repeating circuit according to this invention, detection of the incoming signal is effected by means of a space discharge tube preferably of the cold-cathode type,

2

and pulse repetition is assured through a relay arrangement in the plate circuit of the tube. The moment of beginning of a pulse is determined by the actuation of the cold-cathode tube which causes the initial energization of the relay. The end of the pulse is determined by the falling back of this relay and not by inactivation of the tube. An auxiliary relay which is energized by the operation of the first relay effects the extinction of the tube and also the application to the outgoing line of the current source used to retransmit a signaling pulse train.

For each signaling direction, the pulse repeating or receiving circuit includes a cold-cathode tube fed from the input line through a condenser-transformer series circuit and employs a relay arrangement comprising a two-winding retransmitting anode-relay, an auxiliary relay for internal switching, and a slow relay for neutralizing the signal input equipment of the other channel. With certain modifications, the auxiliary relay may be omitted and its contacts transferred to the anode-relay. One of the windings of this anode-relay is energized by signaling current from the input line by means of a rectifier for holding this relay actuated during the period of the incoming signal.

A circuit illustrating the invention is shown, by way of example, in the single figure of the accompanying drawing.

In the drawing, REP indicates schematically a conventional telephone repeater serving as a coupling for the east-side transmission line E and the west-side transmission line W. Lines W and E are also coupled by two pulse repeating circuits represented by dotted blocks A and A₁ respectively. As will be explained below the circuit of block A is a west-to-east pulse repeater and that of block A₁ is an east-to-west pulse repeater. Three relays, AOR, BOR and COR are actuated during the operation of block A, and of these the function of relay COR is to disable block A₁ when block A is operating. However, as a matter of convenience relay COR is shown in block A₁. Correspondingly a relay CER, which is actuated to disable block A whenever block A₁ is operating, is shown in block A. The relay windings are connected to sources of direct current which may be constituted by a common low-voltage battery B₁ and a high-tension supply B₂. A source of alternating current S, e. g. a 50-cycle generator is connected to contacts b₂ and c₂ of relay BOR. A cold-cathode tube CFO, comprising the cathode Ca, anode An, and auxiliary electrode Ex, has its input connected to the secondary of the

booster transformer TO the primary of which, in series with a condenser CO and a rectifier bridge RD, is connected across the input of the west-side line W.

The invention being explained with reference to the repetition of pulses moving in the west-east direction, only the circuits necessary therefor are fully shown, and the similar circuit for east-west transmission is represented in the drawing by block A₁.

In the operation of the invention, alternating current impulses coming from the west ionize the cold-cathode tube CFO between cathode Ca and auxiliary electrode Ex through the secondary winding of the transformer TO over the following circuit: Back contact *a*₃ of relay CER, rectifier bridge RD by way of left-hand winding of relay AOR, primary of transformer TO, condenser CO. The current will not be strong enough to actuate relay AOR, but the voltage stepped up by the transformer will suffice to effect ionization between cathode Ca and auxiliary electrode Ex of the tube CFO the instant a signal appears. The excitation of the tube results in the passage of anode current from high-voltage source B₂ through the right-hand winding of relay AOR. Thus, the front contact *a*₁ of AOR is closed, which causes the operation of slow-releasing relay COR which, through its back contact *a*₄, disconnects, throughout the duration of the pulse train, the block A₁ devices for preventing the retransmission of pulses in the east-west direction. Front contact *b*₁ of relay AOR is also closed, which establishes a circuit to connect ground to battery B₁ feeding the auxiliary relay BOR, which produces the following operations: First, by opening its contact *a*₂ it inactivates tube CFO. Second, by closing its contacts *b*₂ and *c*₂, it connects the alternating-current source S to wires of east-side line E. After each inactivation of tube CFO, relay AOR remains energized, throughout the duration of the pulse, through its left-hand winding as described.

In the embodiment illustrated, the cold-cathode tube is energized only between the instant each pulse begins and the instant relay BOR operates. As an alternative, however, auxiliary relay BOR might be omitted and its contacts *b*₂, *c*₂ transferred to relay AOR; this would necessitate replacement of high-tension supply B₂ by an equivalent source of alternating current, thus assuring prompt extinction of the tube at the end of each impulse and the provision of a condenser of rather large capacity in shunt to the anode winding, to prevent vibration of the combined relay.

In either case, the rapid operation of relay AOR is effected by virtue of the inertia-free response of tube CFO to the signal voltage, with the aid of the energy taken from high-tension source B₂ or its equivalent. The incoming signal energy, which would be too weak to cause this rapid excitation, is used merely to hold this same relay during the remainder of the pulse. It is clear that, under these conditions, distortion will be particularly low.

The dimensioning of condenser CO and transformer TO will depend on the kind of signal currents which are to be transmitted, i. e., whether they are of commercial or acoustic frequency. It will be understood that these elements may be adjustable so as to respond to frequencies of either range.

While I have shown and described a particular embodiment of my invention, it will be apparent

to those skilled in the art that variations and modifications thereof may be made without departing from the underlying principles of the invention. Thus, although the drawing relates to a repeater, it is quite evident that the system may be used in a terminal station, with suitable modifications consistent with each particular case. I, therefore, desire the following claims to include within the scope of my invention all such substitutions and variations whereby substantially the results of my invention may be obtained by the use of substantially the same or equivalent means.

What is claimed is:

1. A pulse receiving or repeating system for telecommunication networks comprising a tube having a cold cathode, an auxiliary electrode and an anode, means for impressing an incoming signal across said cathode and said auxiliary electrode for causing ionization of said tube, a relay having a winding connected in the cathode-anode circuit of said tube, a local source of current in said circuit for actuating said relay, a second winding on said relay for causing the holding of the relay operated during the signal period, and current rectifying means receiving incoming signal energy and transmitting said energy through said second winding for retaining said relay operated.

2. A pulse receiving or repeating system for telecommunication networks comprising a tube having a cold cathode, an auxiliary electrode, and an anode, means for impressing an incoming signal across said cathode and said auxiliary electrode for causing ionization of said tube, a relay having a winding connected in the cathode-anode circuit of said tube, a local source of current in said circuit for actuating said relay, a second winding on said relay for causing the holding of the relay operated during the signal period, current rectifying means receiving incoming signal energy and transmitting said energy through said second winding for retaining said relay operated, and means controlled by operation of said relay for deenergizing the first winding of said relay and the cathode-anode circuit of said tube.

3. Impulse receiving apparatus comprising first and second transmission lines, means for receiving impulses from the first line and repeating them to the second line, means for receiving impulses from the second line and repeating them to the first line, each of the means for receiving comprising a gaseous discharge tube having a main gap and a control gap, a means for applying received impulses to the control gap to ionize the tube, a local source of potential connected to the tube for energizing the main gap when the tube is ionized, a relay having two windings, means for connecting in series said local source of potential, the main gap and one of the windings for initially operating the relay upon the ionization of the tube, a means for applying the received impulses to the other winding for holding the relay operated for the duration of an impulse, a local source of signaling energy, and a means responsive to operations of the relay for applying impulses from said source of signaling energy to one of the transmission lines in accordance with impulses received from the other, and means responsive when one of the means for receiving is engaged in repeating impulses to prevent the other of them from receiving impulses.

4. Impulse receiving apparatus as in claim 3 in which the impulses received from at least one of the lines are impulses of alternating current having a predetermined frequency, the means for applying those received impulses to the control

gap of one of the tubes comprises a transformer with its secondary connected across said control gap and its primary connected across said one of the lines over a circuit including in series a condenser and the input terminals of a bridge rectifier, said condenser and said primary being tuned to said frequency, and the second winding of the relay initially operated by said tube is connected across the output terminals of said bridge rectifier for holding said relay for the duration of each received impulse by energy derived therefrom over said bridge rectifier.

5. Impulse receiving apparatus as in claim 3 also comprising means responsive to the initial operation of the relay of either of the means for receiving to disconnect from the tube thereof said local source of main gap energizing potential to deionize the tube.

Certificate of Correction

Patent No. 2,498,723

February 28, 1950

CLEMENT M. THEILLAUMAS

It is hereby certified that errors appear in the above numbered patent requiring correction as follows:

In the grant, line 15, strike out "of Seventeen years"; same line, after "grant" insert *until January 8, 1964*; in the heading to the printed specification, line 9, foreign filing date, for "January 7, 1944" read *January 8, 1944*; line 10, before "5 Claims", insert the following: *Section 1, Public Law 690, August 8, 1946, Patent expires January 8, 1964*;

and that the said Letters Patent should be read with these corrections therein that the same may conform to the record of the case in the Patent Office.

Signed and sealed this 22nd day of August, A. D. 1950.
